PROCESS AND APPARATUS FOR DRYING
ARTIFICIAL SILKAdrian J. L. Moritz, Enka, N. C., assignor to
American Enka Corporation, Enka, N. C., a cor-
poration of Delaware

Application July 25, 1934, Serial No. 736,938

13 Claims. (Cl. 34—24)

This invention relates to the drying of artificial silk and the like in package form, and more particularly to a process of and an apparatus for drying unsupported packages of artificial silk in such manner as to cause the yarn to have uniform characteristics throughout the respective packages.

In the past, it has been the practice to subject freshly spun packages of artificial silk to washing and other similar wet treating processes while in package form. Subsequent to the wet treatment of the packages they were dried, and according to the older procedures during the drying the packages were retained in the spinning pots or on bobbins, or as an alternative the packages were placed on drying supports such as the supports employed when drying skeins of artificial silk. Another of the heretofore used methods of drying the packages involved the flattening of the cakes together and the placing of such cakes onto drying frames. In all of these past modes of operation the drying progressed throughout the bodies of the packages in substantially all directions and such drying of packages of artificial silk, when produced by the usual methods of spinning, resulted in the yarns in different portions of the packages possessing different characteristics.

Referring more particularly to the pot spinning process, that is; the process in which artificial silk filaments are extruded from spinnerets and collected in high speed rotating pots, the filaments are collected or as generally termed "spun" into the pots by means of the centrifugal force developed by the rotary speed of the spinning pots. Upon completion of the spinning periods, the steps generally followed during the subsequent treatment of the cakes, involve the removal of the cakes from the pots and the placing of the same in suitable boxes after which they are transferred, while in the boxes, to humidifying chambers for the purpose of conditioning the same. After the humidifying operation, the cakes are removed from the boxes and are tied or laced in such manner as to prevent tangling or breaking of the threads. The cakes are finally placed on bleaching cars and washed and/or desulphurized and bleached. Bleaching cars comprising the type illustrated in United States patent to Engel, No. 1,957,328 are especially adaptable for this purpose.

Cakes treated in the aforementioned manner are now ready for the drying stage and it has been up to the present time, the general practice to employ at this stage the standard step which

involves hanging the cakes on carriers such as aluminum bars or rods and then placing the cakes thus supported in large so-called tunnel dryers. These tunnel dryers are very large and expensive metallic structures and therefore the use of the same is objectionable since the capacity of the dryers does not warrant the large expense involved. Furthermore, when the cakes are dried in such manner, the drying as above stated takes place substantially in all directions.

One decided disadvantage encountered in the use of a method of drying artificial silk cakes, as above referred to is that the yarn in the dried packages does not possess uniform dye absorptive characteristics. The reason for this non-uniform dyeing is attributable to the variable contraction occurring throughout the yarn body of the respective packages. When a drying medium is permitted to contact with an unsupported package of artificial silk from all directions, the outer layers of the package cannot contract to the same extent as the inner layers thereof since the outer layers cannot shrink freely due to the interior of the package being still moist, and more or less rigid, with the result that the filaments or thread of the outer layers meet substantial resistance from the inner layers.

This invention therefore, has as an object the provision of a method of overcoming the above stated difficulties, and the invention contemplates the provision of an improved apparatus for conveniently carrying out the same.

A further object of the present invention is the provision of a drying apparatus for artificial silk wherein the drying action progresses within the artificial silk packages only from the inside to the outside thereof.

The invention still further contemplates an apparatus in which the ordinary cake supporting boxes are positioned in contact vertically one above the other and are then placed bodily in position in connection with the remainder of the drying apparatus, whereby the sides of the cake boxes serve to function as sections which collectively form a drying chamber.

An additional object of this invention is provision of an apparatus having relatively light weight sectional drying chambers whereby they are readily portable.

Other advantages and objects will be apparent from the following detailed description, and considered in connection with the accompanying drawings wherein:

Fig. 1 is a side elevational view showing the built-in air heating and circulating system with

its full capacity of portable sectional drying columns formed of the cake boxes arranged in operative position.

Fig. 2 is a top plan view of the apparatus shown in Fig. 1.

Fig. 3 is an end view of the same apparatus as illustrated in Fig. 1.

Fig. 4 is an end view of the apparatus opposite to that shown in Fig. 3.

Fig. 5 is a transverse sectional view taken on line 5-5 of Fig. 1.

Fig. 6 is an enlarged longitudinal fragmentary sectional view taken on line 6-6 of Fig. 2.

Fig. 7 illustrates a series of cake boxes formed into a drying column.

Fig. 8 illustrates a complete set of cake boxes mounted on a transporting jack truck by which the filled columns may be moved into or out of the operative position with respect to the remainder 20 of the drying system.

Fig. 9 is a perspective view of one of the platforms provided for use with each two columns of cake boxes.

Fig. 10 is a perspective view of one of the doors 25 used in conjunction with each platform supporting a set of outer columns of cake boxes.

Fig. 11 is a detailed sectional view showing the manner in which a door is secured to an outer platform, and

Fig. 12 is an enlarged detailed sectional view through a portion of one of the drying columns.

Now referring to the drawings in detail, the numeral 10 designates a conventional type air heating unit which may be formed with a plurality of tubes for conducting steam or other heating fluid. The temperature and volume of the heating medium is subject to control and is preferably controlled automatically in order that the air to be utilized as the drying medium may 40 be heated to the desired degree notwithstanding any change in the volume of the air being passed through the system.

The air is caused to be passed through the heating unit 10 by means of a fan 11 arranged in fan 45 casing 12, and the fan may be operated by any well known power means (not shown). As the fan is operated the air will be drawn into the fan casing 12 and will then be forced from the casing through a conduit 13, after which it will be forced 50 through the heating unit and will be heated to the desired extent. The air current produced by the fan causes the air to flow from the heating unit into an overhead duct 14 which is formed with a decreasing cross section as shown in Fig. 1, and which duct is further formed with a plurality of similarly constructed offtakes or branch pipes 15.

Although each of the branch pipes 15 is of the same size and is arranged progressively along the 60 duct 14 as the duct is decreased in cross section so that there is a tendency for the air flowing into the duct to be equally divided between the branch pipes 15, each branch pipe, nevertheless, is provided with a valve or damper 16 which provides for the control of the passage of air there- 65 through.

Branch pipes 15 are each provided with a series of outlet fittings 17 each of which has extending therefrom an accordion type flexible connection 70 18 and a conical hood 19. These conical hoods 19 are adapted to be raised or lowered due to the extending or contracting of the respective connections 18, and when lowered they are each adapted to engage with one of a series of sectional 75 drying chambers indicated generally at 20, the

construction of which chambers will be hereafter fully described.

As shown in Fig. 5, transversely arranged rows of chambers 20 are positioned so that the chambers of each row have their lower ends communicating and each of the communicating passageways opens into one of a series of extensions 21 provided on a return duct 22. The return duct is formed with a gradually increasing cross-section in the direction of the fan casing 12 and it is provided at its largest end 23 with a connecting conduit 24 which opens centrally into fan casing 12.

A discharge pipe 25 is connected to the conduit 13 while a fresh air inlet 26 is connected into the end 23 of return duct 22. Valves or dampers 27 and 28 are arranged to control the passage of air through the discharge pipe 25 and inlet 26 respectively and these valves are arranged for simultaneous operation by means of a rod 29 which connects the operative handles 30 and 31 of the valves.

In operating the drying system as thus far described, the air heating unit 10 is first rendered effective by the passage of the heating fluid through the tubes therein and the fan is caused to be rotated whereupon the air in the system is caused to be circulated first through the heating unit and then in its heated condition, into the duct 14. The heated air in duct 14 is divided and portions thereof are passed through the branch pipes 15. Heated air passing in each branch pipe becomes further divided and a portion of the air is passed through each of the connections 18 and through the drying chambers 20. The separate portions of air as they pass from each transverse row of drying chambers are collected and passed into the return duct 22 where the air from the various transverse rows of chambers is intermingled and drawn to the fan casing 12 for recirculation. In order to keep the system efficient even after long periods of usage, some of the moisture laden air is caused to be discharged through the outlet pipe 25 and due to the setting of the valves 27 and 28, an equal amount of fresh air is drawn into the system.

The condition of the cakes of yarn being dried can be readily determined by raising a cover at the top of a chamber in any of the transverse rows and, should it be determined that the drying of the cakes in the different transverse rows of chambers is not proceeding regularly with respect to other rows, this can be compensated for by a manipulation of one or more of the valves 16.

While the system has been described with the air circulating therein in such manner that the heated air flows downwardly in the sectional chambers 20, it is to be understood that the operation may be reversed so that an up draft will be had in the respective chambers. In such an operation the pipe 25 would act as an inlet pipe while air would be discharged from the opening 26 when the respective valves 27 and 28 are open.

The construction of the drying chambers 20, and the steps involved in the handling of the cakes of artificial silk yarn are important features of this invention and in order to give an example of one detailed form of the construction and of a detailed method of procedure, reference will be had to the drawings. Each chamber 20 is made up of a number of trays 32 which, in the form shown, are oblong. Trays 32 each have side walls 33 which are preferably con-

structed of wood or some other relatively light and inexpensive material resistant to heat conduction. A frame 34 of angled metal, preferably of a type which does not corrode, is secured 5 to the lower edges of the side walls 33 of each tray in such manner as to cause the frame to project below the side walls, as indicated at 35, with the angled webs thereof forming a ledge 36. Mounted on the ledge 36 is a bottom 37 10 preferably formed of pressed fiber board, said bottom 37 being provided with a series of equally spaced openings 38. One opening 38 is provided for each cake of yarn to be dried and in the specific form shown each tray 32 is constructed to 15 hold twelve cakes. A cover 39 is provided for each tray and the cover may be formed like the bottom 37 of pressed fiber board. The covers 39 are formed of substantially the same size as the bottoms 37 and they are also provided 20 with openings 40 of the same size as the openings in the bottom. Covers 39 are adapted to be placed upon the cakes of yarn when they have been arranged within the trays and as the openings 38 and 40 are in registry when a tray and 25 its cover are assembled, and, since the openings in each are spaced so that each tray will accommodate twelve cakes with their center openings coaxial with the openings 38 and 40, each filled tray and cover assembly will have twelve confined passageways therethrough.

Due to the projection of the frames 34 below the walls 33 of the respective trays 32, each frame acts as an aligning and retaining member for holding its tray in position upon a lower 35 tray since each frame 34 will be partially received within the walls of a lower tray above its cover 39. When a number of filled trays 32 are stacked one upon another in the manner just described, they form a drying chamber having 40 twelve channels therethrough which channels are largely defined by the interior walls of the cakes of yarn.

In order to permit of the assembly of filled trays into complete drying chambers in such 45 form that they can be readily transported and incorporated into the drying system having the heated air circulated therethrough by the fan 11, as above described, the lowermost tray 32 of each stack is placed on a platform 41 which is 50 adapted to rest directly upon the floor of the assembly room. The platform has wooden sides 42 which are of such length that the platform provides a base for two of the stacks of trays. Bars 43 are arranged at the ends of the platform 55 and bar 44 of greater width is arranged at the center of the same. The center bar 44 is mounted on webs of angle bars 45 which are secured to the sides 42, and the end bars 43 are reinforced with angle bars. At each corner angle 60 bars 46 are provided, and longitudinal angle bars 47 extend throughout the length of each platform to provide reinforcements for permitting a platform with two stacks of trays arranged thereon to be elevated and transported by means 65 of a jack truck 48 of the usual well known construction.

After a platform 41 has had two stacks of filled trays 32 arranged thereon a conical cover 49 is positioned on each stack of trays with its flange 50 being received within the walls 33 of the uppermost tray. The jack truck 48 is then moved under the platform with its elevating mechanism extending under the angle bars 47. Raising of the platform 41 and the load thereon is then effected by manipulation of the jack truck and the

loaded platform is then moved with the truck to a position where one of the open ends of the platform is abutted against an abutment board 51. Due to the employment of alignment strips 52 the platform when in position between the strips will be so aligned that the open end of the platform will be in communication with a duct extension 21 on the return duct 22. Furthermore, the alignment strips 52 will cause the end of the platform to abut evenly against the board 51 so that a prohibitive amount of heated air will not escape at this joint during the operation of the system.

After the loaded platform has been lowered into position the truck 48 is withdrawn and returned to the assembly zone for transporting another loaded platform. During this period the conical hoods 19 are lowered into position upon the conical covers 49 and a reasonably tight joint is produced. The next loaded platform is then positioned in front of the platform first transported, and the second platform is lowered into the position between the same alignment strips 52 with its inner open end abutting the end of the first platform. The joint between the ends of the two platforms is also reasonably airtight due to the manner of abutting the ends. Hoods 19 are now lowered over the conical covers on the stacks of the second mentioned platform.

Since the second mentioned or forward platform is now open at its outer end, a door 53 is abutted against the angle bars 46 and latch members 54, having operating handles 55, are turned into a position so as to clamp over the webs of the respective angle bars 46 for holding the door in closed position. With the door 53 in position the arrangement as described results in the formation of one transverse row of sectional drying chambers 20 above referred to in connection with the description of the general drying system. 40 The remaining transverse rows of drying chambers may now be formed and placed in position in the manner described in connection with the first transverse row of chambers.

When each of the stacks of trays or chambers 45 are in position, the hoods 19 lowered, and the doors 53 are all in place, the heating unit 10 is caused to be operated and the fan 11 is rotated whereupon the air is passed through the heating unit and into the duct 14. The heated air is then divided as described above and, as a division of the heated air passes into each stack of filled trays comprising a drying chamber 20, the division of air is distributed by the stack cover 49 so that further divided currents of the air are caused to pass through openings 40 in the cover 39 arranged in the uppermost tray of the stack. In the specific apparatus illustrated a current of heated air will pass through each of the twelve openings 40 and, as this heated air passes 60 through the openings, it contacts with the interior layers of thread in the respective cakes. Since the interiors of the cakes are thread free, the air after taking up some of the moisture from each cake passes through the respective openings 38 in the tray bottom 37. In the space between the bottom 37 of the upper tray and the cover 39 of the next lower tray, the several currents of air become somewhat intermingled, but the air is again divided and separate currents 65 thereof pass downwardly through the openings in the cover of said next lower tray and through the thread free centers of the cakes in the tray whereupon they then pass through the openings in the bottom of the tray and become somewhat 70 75

intermingled between the bottom of the last mentioned tray and the cover of the next lower tray. This described passage of air takes place in each chamber 20 and the division of the air passing in each chamber continues to flow through the stacked trays until it flows from the openings in the bottom of the lowermost tray whereupon the respective currents of air from each of the drying chambers in respective transverse rows are collected together within the opening provided by the abutted platforms 41. The collected air currents are now drawn into the return duct 22 in which the air becomes further intermingled with the air being returned from other transverse rows of drying chambers. The collected air is recirculated through the system and, when necessary, a portion thereof is discharged from the system and replaced by a fresh portion of air in accordance with the operation 20 specifically referred to above.

During the drying of cakes of artificial silk thread in the respective sectional columns 20 a contraction of each cake takes place with the result that the respective covers 39 settle within 25 the respective trays and thereby maintain the spaces in the trays which surround the cakes substantially free of air currents whereby the drying action within each cake takes place progressively from the inside to the outside thereof. 30 Due to the lack of air currents in contact with the exteriors of the cakes, the moisture as it is removed from the cakes is largely withdrawn through the interior layers of threads. Such a drying operation causes the interior layers of 35 threads in the cakes to first contract as the drying proceeds, and the contraction takes place progressively toward the outside of the cakes whereby by the initial contraction of the inner layers of threads resistance to contraction of the outside 40 layers is avoided.

After the drying operation has proceeded to the desired extent the operation of the system may be discontinued, the doors 53 removed from the front platforms, and the hoods 19 raised 45 after which a truck 48 may be placed into position under a desired platform, and the platform with the stacked trays thereon may be removed with the truck to the place used for the unloading of the dried cakes from the trays. This procedure may be continued until all of the trays 50 are emptied and another operation may be started by the refilling of the trays with wet cakes and the placing of the trays in operative position and starting the system. It will be readily understood that should it be desired the system may be 55 operated for drying cakes in any selected number of transverse rows of drying chambers while other chambers are being placed in position or are being removed from the system. Such an operation can be carried out by utilization of the dampers or valves 16 in the respective branch pipes 15.

What I claim is:

1. A method of drying cakes of artificial silk 65 thread and the like to cause the thread therein to have uniform drying from the inside to the outside thereof which comprises arranging cakes of artificial silk in trays, positioning the trays one upon another to form a substantially air tight stack, passing separate currents of drying gas through the thread free interiors of cakes arranged in one of the trays, commingling the gas of said currents to assure substantial uniformity of moisture content of the gas, dividing the body 70 of commingled gas, passing the divisions of gas 75

as separate currents through the thread free interiors of the stacked cakes in adjacent trays, and maintaining the air in contact with the exterior of the cakes substantially quiescent and in a confined state whereby drying proceeds through the body of the cakes by permeation of the said heated gas only. 5

2. A portable sectional drying chamber for textile cakes and the like adapted to be incorporated in a drying system comprising a series of separable 10 trays each adapted to support a plurality of textile cakes, openings in the bottoms of the trays adapted to communicate with the thread free interiors of the respective cakes, a cover for each tray freely movable therein and adapted to be 15 supported by the respective cakes, said covers each being provided with openings registering with corresponding openings in the tray bottom, said trays being arranged one upon another to form a stack, and independent means for maintaining the trays in the stacked position. 20

3. A portable sectional drying chamber for textile cakes and the like adapted to be incorporated in a drying system comprising a series 25 of trays each adapted to support a plurality of textile cakes, openings in the bottoms of the trays adapted to communicate with the thread free interiors of the respective cakes, a cover for each tray freely movable therein and adapted to be supported by the respective cakes, said covers each being provided with openings registering with corresponding openings in the tray bottom, said trays being adapted to be arranged one upon another to form a stack with spaces existing 30 between the respective covers and the next adjacent tray to form zones to permit intermingling of currents of drying medium after passage thereof through the interiors of cakes adjacent said spaces, means for maintaining the trays in the stacked position, and a hood fitting into the 35 uppermost tray of the stack above the cover for said tray, said hood being reduced at its upper end to a conduit adapted for connection to the system. 40

4. A portable sectional drying chamber for textile cakes and the like adapted to be incorporated in a drying system comprising a series of trays 45 each adapted to support a plurality of textile cakes, openings in the bottoms of the trays adapted to communicate with the thread free 50 interiors of the respective cakes, a cover for each tray adapted to be supported by the respective cakes and provided with openings registering with each opening in the tray bottom, said trays being arranged one upon another to form a 55 stack, and means on each tray for supporting the bottom thereof, said supporting means extending below the side walls of the tray and into the next adjacent lower tray for maintaining the trays in stacked condition. 60

5. A portable sectional drying chamber for textile cakes and the like adapted to be incorporated in a drying system comprising a series of trays each adapted to support a plurality of textile cakes, openings in the bottoms of the trays adapted to communicate with the thread free interiors of the respective cakes, a cover for each tray adapted to be supported by the respective cakes and provided with openings registering with each opening in the tray bottom, said trays being arranged one upon another to form a stack, means 65 on each tray for supporting the bottom thereof, said supporting means extending below the side walls of the tray and into the next adjacent lower tray for maintaining the trays in stacked condition. 70

75

tion, and a hood for the stack fitting into the uppermost tray above the cover thereof and provided with a reduced passageway at its upper portion to permit connection of the stack to the drying system.

6. A retaining tray for cakes of artificial silk and the like capable of functioning as a section of sectional drying chambers comprising side walls, a bottom provided with a series of substantially equally spaced openings, and a cover closely fitting within the side walls and freely movable toward and away from the bottom, said cover being provided with openings in registry with the openings in the bottom, thereby forming a space for the reception of cakes of artificial silk to be positioned in the tray with the thread free interiors thereof in communication with the openings in the bottom, and the cover contacted with the cakes whereby access to the interiors of the cakes will be had to permit the passage of drying gas therethrough.

7. A retaining tray for cakes of artificial silk and the like capable of functioning as a section of sectional drying chambers comprising side walls, a bottom provided with a series of substantially equally spaced openings, a support for the bottom which extends downwardly as a flange below the lower edges of the side walls so as to form a substantially tight fit with another tray when placed thereon with the support extending thereinto, and a cover fitting within the side walls and freely movable toward and away from the bottom, said cover being provided with openings in registry with the openings in the bottom whereby when cakes of artificial silk are positioned in the tray with the thread free interiors thereof in communication with the openings in the bottom and the cover is contacted with the cakes, access to the interiors of the cakes will be had to permit the passage of drying gas therethrough.

8. A portable drying section for cakes of artificial silk and the like adapted to be incorporated in a drying system comprising platforms abutted together and provided with communicated openings in the walls thereof, said platforms having adjacent openings in their upper walls and having their remote walls respectively when in abutted relation provided with a removable section and an opening for permitting communication with a duct of a drying system, a plurality of substantially gas tight stacks of trays mounted on each platform with the lowermost tray of each stack being positioned over one of the openings in the upper walls of the platforms, the trays of each stack being formed with bottoms having openings therein and being constructed to receive artificial silk cakes with the thread free interiors thereof in communication with the openings in the tray bottoms, and a hood mounted on the top of each stack, each of the hoods being provided with a reduced portion adapted for connection to a drying system.

9. A portable drying unit for cakes of artificial silk and the like adapted to be incorporated in a drying system comprising a platform having an opening through the center thereof and two adjacent openings in its top, stacks of trays mounted on the platform with

the lowermost tray of each stack being positioned over one of the openings in the top of the platform, the trays of each stack being formed with bottoms having a plurality of openings therein, means for retaining the trays in the stacks and for rendering the joints between the trays substantially gas-tight, said trays being constructed to receive artificial silk cakes with the thread free interiors thereof in communication with the openings in the tray bottoms, and a hood mounted on the top of each stack, each of the hoods being provided with a reduced portion adapted for connection to a drying system.

10. A drying system for cakes of artificial silk and the like comprising a fixed section including a delivery duct for drying gas, a return duct for the drying gas, means for heating the gas passed to the delivery duct, branch pipes connected to the delivery duct, a plurality of bodily movable sectional drying chambers arranged between outlets on the branch pipes and the return duct, valves for controlling the passage of gas through the respective branch pipes, said sectional drying chambers being formed of substantially gas tight stacked trays, each of which trays is constructed to retain a plurality of cakes of artificial silk in a manner to cause the drying gas when conducted through the chambers to contact with the cake surfaces defining the thread free interiors thereof while substantially preventing contact of the gas with the exterior surfaces of the cakes, and a cover within each tray mounted to provide a space between it and the next adjacent tray to permit the commingling of the currents of drying gas after the gas has passed through cakes of artificial silk in one tray and before the gas is further divided and passed through cakes of artificial silk in another tray.

11. A drying system according to claim 10 which further comprises means for flexibly and detachably connecting the uppermost tray of each stack to the branch pipes of the delivery duct.

12. A drying system according to claim 10 which further comprises means for forming an air tight juncture between the inlets and outlets of the heated drying gas and the stacks of cakes to be dried.

13. A method of drying artificial silk thread and the like in cake form to cause the thread therein to be uniformly dried from the inside to the outside thereof which comprises dividing a volume of drying medium and passing separate currents thereof through the thread free interiors of a plurality of cakes of artificial silk, commingling the currents of drying medium after passage through the cakes, further separating the drying medium and passing the same through the thread free interiors of another plurality of cakes, and maintaining air in contact with the exteriors of the cakes in substantially a quiescent condition whereby initial drying of the exterior of the cakes is substantially eliminated and the cakes are dried progressively from the interiors to the exteriors thereof.

ADRIAN J. L. MORITZ.
